UNITED STATES PATENT OFFICE.

PHILIP J. HANDEL, OF MERIDEN, CONNECTICUT.

DESIGN FOR A LAMP BRACKET OR STANDARD.

SPECIFICATION forming part of Design No. 36,133, dated November 4, 1902.

Application filed August 13, 1902. Serial No. 119,579. Term of patent 7 years.

To all whom it may concern.

Be it known that I, PHILIP J. HANDEL, a citizen of the United States of America, residing at Meriden, in the county of New Haven and State of Connecticut, have invented a new, original, and ornamental Design for Lamp Brackets or Standards, of which the following is a specification.

As shown in the drawings, the leading or material features of my design consist in a representation of a pond-lily blossom and a pond-lily bud supported on separate stems which spring from a suitable base. This base is in the form of a pond-lily leaf.

Having described my invention, what I claim as new, and desire to secure by Letters Patent, is—

The ornamental design for a lamp bracket or standard substantially as shown and described.

In testimony whereof I affix my signature in presence of two witnesses.

PHILIP J. HANDEL.
